CAR STOP

Paul J. McCullough, St. Louis, Mo., assignor to
Joseph Pavelka, Sr., St. Louis, Mo.

Application July 3, 1937, Serial No. 151,793

15 Claims. (Cl. 104—258)

The invention relates to car stops adapted to be placed at a selected point on top of a car rail and clamped thereto to engage the wheel of a car to limit the movement of the car along the rail.

5 One of the objects of the invention is to facilitate the application and removal of a stop of the type referred to.

Another object of the invention is to simplify such stop structure and to minimize the cost thereof.

10 These and other detailed objects of the invention will be apparent from the following description of the device, reference being had to the accompanying drawing, in which—

15 Figure 1 is a front elevation of the stop showing the same in position on a rail.

Figure 2 is a similar elevation showing the holding device in released position.

20 Figure 3 is a side elevation of the structure as shown in Figure 1.

Figure 4 is a similar elevation illustrating a modified structure.

25 Figure 5 is a vertical section taken approximately on the line 5—5 of Figure 4.

The device illustrated in Figures 1, 2 and 3 comprises a body structure 1, having a base 2 adapted to rest upon the top of a head of a track rail 3, the body including forwardly and rearwardly facing surfaces adapted to contact with the wheel of a car mounted upon the track. Lugs 4 and 5 depend from body 1, and lug 4 includes a 30 jaw 6 arranged to project beneath the rail head. The other lug 5 has its inclined edge shaped to permit the device to be moved into position on the rail head with jaw 6 opposing the underside of the head as shown.

35 A rod 7 is passed through an aperture 8 in the body structure and is then bent at right angles at the sides of the body to form a lever handle 9 and a hook 10 respectively. When the handle is raised, as shown in Figure 2, hook 10 will be moved away from jaw 6 so as to permit the device to be applied to a rail or removed therefrom. When the handle is lowered, as shown in 40 Figure 1, hook 10 will be moved towards jaw 6 to hold the device onto the rail.

45 A coiled spring 11 is compressed between a bracket 12 on handle 9 and the opposing face of the body, being positioned on the latter by a projection 13. Spring 11 and the rod structure have a snap action whereby the handle and hook are yieldingly held in one of the two positions indicated, pins 14 serving to limit the movement of the handle in opposite directions from an intermediate neutral point.

If desired, a padlock 15 may be applied through an aperture 16 in the body to prevent upward movement of handle 9 and thereby maintain hook 10 beneath the rail head and prevent removal of the device from the rail except by an authorized person.

In the modification illustrated in Figures 4 and 5, the body structure is made of a plurality of relatively thin plates having substantially the same contour as the cast or forged body structure 10 shown in Figures 1 to 3. The outer plates 21 and 22 have an aperture corresponding to aperture 8 in the body structure previously described, and the intermediate plates 23, 24 and 25 are recessed inwardly from their lower edges, as indicated at 26. Plates 23, 24 and 25 are also recessed inwardly from their lateral edges, as indicated at 27, to form, with the unrecessed outer plates 21 and 22, a pocket for receiving the end of coiled spring 28. Preferably the middle plate 20 24 has a tongue 29 for entering the spring to position the same against movement transversely of its axis.

The operating lever 30 corresponds to that shown in Figures 1 to 3 and may be given its 25 final form before assembly with the body structure if the plates comprising the latter are not secured together until the handle is assembled therewith. The two outer plates 21 and 22 may be passed separately over the hook end of the 30 lever into the position shown in Figure 4, and the intermediate plates 23, 24 and 25 may be inserted between plates 21 and 22 and moved transversely of the journal portion of the lever into the position shown. All of the plates can then be 35 riveted together, as indicated, to form a substantial body structure.

In both forms of the invention, the base of the stop is relatively narrow, longitudinally of the rail, and the wheel opposing face of the stop is 40 relatively wide transversely of the rail. There is sufficient clearance between the rail head and lugs 4 and 5 and jaw 6 to permit the stop to tilt from its upright position longitudinally of the rail and to twist from its normal position 45 with its wheel engaging face at right angles to the rail. Since the wheel engaging face of the body extends laterally a substantial distance beyond the edge of the rail head, the body will first be engaged by the wheel flange, tending to twist 50 the body from its normal transverse position. Also the upright portion of the body will be engaged by the wheel, which tends to tilt the body from its upright position. These twisting and 55 tilting movements result in clamping the rail be-

55

tween opposed lugs 4 and 5 and between the jaw 6 and base 2. Thus the device is securely clamped to the rail and held against movement longitudinally thereof by rigid elements and independently of the movable latching element which merely serves as a retainer to temporarily hold the device upright and prevent its accidental dislodgment from the rail.

- It is obvious that the device is very simply constructed and readily applied to the rail and secured in position by a single movement of the operating lever. When it is desired to remove the device, it is just as simply released. It is unnecessary to drill any holes in the rail or to utilize tools of any kind in applying and removing the stop. The device is readily operated in close quarters and is therefore particularly adapted for use on mine car tracks where there is relatively little clearance at the side of the track.
- 20 The device may be modified substantially in appearance and in detail construction from the arrangement illustrated and described without departing from the spirit of the invention and exclusive use of such modifications as come within 25 the scope of the claims is contemplated.

What is claimed is:

1. A car stop comprising a block arranged to rest upon the top of a rail and having wheel engaging elements, a rail engaging member rigid with and depending from said block, and a co-operating latch lever pivoted directly on said block at a point spaced from the wheel engaging elements and said member and including a hook movable into and out of position to engage the rail to hold the block thereon, there being spring means for yieldingly holding said latch and hook in rail engaging position or in released position.
2. A car stop comprising a block arranged to rest upon the top of a rail head and having a jaw 40 to engage the side and bottom of said head, said block having a wheel engaging surface, and a latch lever pivoted directly on said block at a point spaced from said surface and including a hook movable towards and away from said jaw 45 to cooperate therewith in securing the block to the rail head, there being a spring compressed between the block and the latch and arranged to thrust the latch downwardly and the hook inwardly or to thrust the latch upwardly and the hook outwardly when the latch is moved to one side or the other of an intermediate neutral position.
3. A car stop comprising a block adapted to stand upright upon a rail and having a wheel engaging face and depending lugs for straddling the rail, a locking device comprising a rod journaled in said block on an axis perpendicularly to said wheel engaging face and at one side of said block extending downwardly and terminating in 55 a rail engaging hook and at the other side of said block extending outwardly to form an operating handle, said rod being operable by said handle about said axis to move said hook into and out of rail engaging position, there being spring means for yieldingly holding said handle and hook in rail engaging position or in released position.
4. In a car stop, a wheel engaging block adapted to rest upon the top of a rail, opposing elements for engaging opposite sides of the rail to hold the 60 block thereto, one of said elements being pivotally mounted on said block and movable into and out of functioning position, and spring means providing a snap action for said pivotally mounted element tending to hold it in either position.
75. 5. In a car stop, a wheel engaging block adapt-

ed to rest upon the top of a rail, opposing elements for engaging opposite sides of the rail to hold the block thereto, one of said elements being pivotally mounted on said block and movable into and out of functioning position, and spring means 5 providing a snap action for said pivotally mounted element tending to hold it in either position.

6. In a car stop, a wheel engaging block adapted to rest upon the top of a rail and including a depending jaw for engaging one side of the rail, 10 a hand lever pivoted on said block and movable in a vertical plane and extending laterally beyond said block, for manual manipulation, a spring compressed between said lever and said block and tending to hold said lever in raised position or in lowered position, and a hook actuated by said lever when lowered for engaging the opposite side of the rail to hold said block upright thereon.

7. In a car stop, a body structure adapted to 20 rest upon a rail and comprising a plurality of plates arranged side by side and including depending elements for engaging one side of a rail head, a rod extending through said plates and bent at right angles at the sides of said structure 25 to form respectively a hand lever and a latch for engaging the other side of the rail, some of said plates being apertured to permit their application to said rod endwise of the latter, the apertures forming circular bearings for the rod, and others 30 of said plates being slotted inwardly from their edges to permit their application over said rod transversely of its axis.

8. In a car stop, a body structure adapted to rest upon a rail and engage one side face thereof, 35 a rod extending through said structure and bent at right angles at the sides of said structure to form respectively a hand lever and a latch for engaging the other side of the rail, said structure comprising a series of plates, the outer of which 40 are apertured to have said rod pass through them, there being plates inserted intermediate said outer plates to hold the same spaced apart, said intermediate plates being recessed inwardly from their edges to permit the movement of said rod laterally to a point spaced inwardly from said edges.

9. In a car stop, a body structure adapted to rest upon a rail and engage one side face thereof and comprising a plurality of plates arranged 50 side by side, a rod with a section extending through and journaled in said structure and with sections extending along opposed sides of said structure to form respectively an operating handle and a hook for engaging the other side of the rail head, a spring compressed between the edge of said body structure and said handle to hold the same in extreme positions of its pivotal movement, some of the intermediate plates being notched at their edges to seat one end of said 60 spring between the outer unnotched plates.

10. In a car stop, a body structure adapted to rest upon a rail and engage one side face thereof and comprising a plurality of plates arranged side by side, a rod with a section extending through 65 and journaled in said structure and with sections extending along opposed sides of said structure to form respectively an operating handle and a hook for engaging the other side of the rail head, a spring compressed between the edge of 70 said body structure and said handle to hold the same in extreme positions of its pivotal movement, one of the intermediate plates being notched inwardly of its edge to receive the end of said spring and having a tongue projecting 75

from the inner portion of said notch to enter said spring and position it transversely of its axis.

11. A car stop comprising a body arranged to rest upon a rail and having a wheel engaging member and a rigid element for engaging one side of a rail, a latch pivoted on said body and including a hook movable into and out of position to engage the other side of the rail to hold the body thereon, and spring means yieldingly holding said latch and hook in rail engaging position.

12. A car stop comprising a body having a base for resting upon a rail and an upstanding face for engaging a wheel, said base being relatively narrow lengthwise of the rail and said face being relatively wide transversely of the rail to project laterally beyond the rail head into position to be engaged by a wheel flange, and rigid projecting elements arranged to receive between them laterally and downwardly facing portions of the rail and providing for tilting of the stop longitudinally of the rail from an upright position and for twisting of the stop from a normal transverse

position whereby the body may be clamped at the rail and held against movement along the rail.

13. A car stop as described in claim 12 which also includes means in addition to said rigid projecting elements for retaining the stop on the rail when there is no car wheel pressure against the stop.

14. A car stop comprising a body with a base arranged to rest upon a rail and including a wheel engaging member extending upwardly from said base and rail, opposing elements rigid with 10 said member and extending downwardly and inwardly from said base and arranged to loosely receive between them a rail head and adapted to clamp the rail head when said body is tilted and twisted on the rail.

15. A car stop as described in claim 14 which also includes a latch pivoted on said body and provided with a hook movable into and out of position to cooperate with one or more of the rail opposing elements to hold the body thereon, and 20 spring means yieldingly holding said latch and hook in such cooperating position.
